United States Patent

Des. 241,582
Patented Sept. 21, 1976

241,582

KEY CASE

Lynn Stark, 21614 85th St. SW.,
Edmonds, Wash. 98020

Filed Nov. 27, 1974, Ser. No. 527,563

Term of patent 14 years

Int. Cl. D3—01

U.S. Cl. D87—8

FIG. 1 is a front perspective view of a key case embodying my new design.

FIG. 2 is a perspective view of the key case in its normally closed position.

FIG. 3 is a rear perspective view as viewed from the side opposite FIG. 1.

I claim:

The ornamental design for a key case, substantially as shown.
